DESIGN FOR A THERMOSTAT CASING

George W. Crise, Columbus, Ohio, assignor
to Crise Electric Manufacturing Company,
Columbus, Ohio

Application March 26, 1943, Serial No. 109,819

Term of patent 14 years

To all whom it may concern:

Be it known that I, George W. Crise, a citizen
of the United States, residing at Columbus, in
the county of Franklin and State of Ohio, have
invented a new, original and ornamental Design
for a Thermostat Casing, of which the following
is a specification, reference being had to the accompanying
drawing, forming a part thereof.

Fig. 1 is a front elevational view of the thermo-
stat casing showing my new design;

Fig. 2 is a side elevational view thereof;
Fig. 3 is a top plan view;
Fig. 4 is a bottom plan view;
Fig. 5 is a horizontal sectional view on the line
5—5 of Fig. 1.

I claim:

The ornamental design for a thermostat casing,
as shown.

GEORGE W. CRISE.
